IDENTIFICATION ORNAMENT

William Forstner, Irvington, N. J., assignor to
Forstner Chain Corporation, a corporation of
New Jersey

Application February 21, 1938, Serial No. 191,638

4 Claims. (Cl. 40—140)

My present invention relates to identification ornaments such as identification tags for use with key chains and the like, and has particular reference to a novel construction for selective ornamentation.

It is the principal object of my invention to provide an ornament holder suitable for use as an identification ornament, in which selected ornaments, as for example initial letters, may be readily mounted.

It is a further object of my invention to provide a simplified construction for identification ornaments, which may be made in a variety of materials, as for example leather, metal, and the like.

It is an additional object of my invention to provide a construction which will retain a selected ornament against accidental detachment or separation, while permitting ready mounting of the selected ornament thereon.

Another object of my invention is to provide a simplified construction which may be readily manufactured with standard shop machines, thus reducing the cost of manufacture.

With the above and other objects and advantageous features in view, my invention consists of a novel arrangement of parts more fully disclosed in the detailed description following, in conjunction with the accompanying drawing, and more specifically defined in the claims appended thereto.

In the drawing:

Fig. 1 is a plan view showing the novel invention as applied to a keyring tag;

Fig. 2 is a side view thereof;

Fig. 3 is an enlarged sectional detail on the line 3—3 of Fig. 1;

Fig. 4 is a perspective view of a leather ornament container;

Fig. 5 is a perspective view of the top clamp member;

Fig. 6 is a perspective view of an ornament base;

Fig. 7 is a perspective view of an ornament for mounting on said base;

Fig. 8 is a perspective view of a modified base construction;

Fig. 9 is a plan view of a modified identification ornament assembly;

Fig. 10 is a perspective view of an ornament for use therewith;

Fig. 11 is a perspective rear view of the cover for use therewith; and

Fig. 12 is a perspective view of the modified ornament bases.

It has been found desirable to provide a novel construction for identification tags or the like, which utilizes an ornament base on which one or more selected ornaments may be readily mounted, the ornament base and the selected ornament being enclosed in a frame designed to display the ornament, and at the same time lock the ornament in place so as to prevent accidental removal or separation.

The container functions both as a container and as a locking member, and therefore can be made of a variety of materials, two preferred materials illustrated in the drawing being leather and metal.

Referring to the drawing, the novel identification ornament 15 has a plurality of selected ornaments 16, the illustration disclosing initials, and is connected by means of a connecting member 17, which preferably is in the form of a flexible chain, to a keyring or the like 18. The identification ornament includes an outer container 19, see Fig. 4, which when made of leather is composed of two layers 20 and 21 sewed together at the sides, as indicated at 22, to provide a container having an opening 23 between the two layers at the lower end thereof, and a corresponding opening 24 at the upper end thereof, the upper layer 20 being cut as indicated at 25 to form an ornament retention frame.

An ornament base 26, see Fig. 6, is preferably stamped out of sheet metal stock, and has two aligned flanges 27, preferably struck up from the stock, and having their adjacent edges 28 turned towards each other and spaced from the body of the base, the upper end of the base being shaped 35 to conform to the shape of the container 19, and terminating in a head 29 which has an opening 30 therethrough for receiving one end of the chain connection 17. An ornament 31, see Fig. 7, preferably in the form of an initial letter, is made 40 from sheet metal stock, but may be of any suitable material, and has grooves 32 at the upper and lower edges thereof, which cooperate with the edges 28 to permit sliding engagement of the ornament with the base.

As illustrated, two initial letters may be positioned on the base, note Fig. 1, but any number of initial letters may be used by properly proportioning the width of the letters and of the base; other ornaments may, if desired, be used 50 in place of letters. With the ornament letters slidingly mounted on the base, the base and its letters are passed through the container 19 until the frame 25 encloses the flanges 27 and engages the sides of the ornament letters, so as to lock 55

the ornament letters against lateral movement, the head 29 projecting from the container. An end closure 33, preferably of stamped metal, and having an opening 34 and prongs 35, is then positioned with the head 29 passing through the opening 34, and is then bent over, as shown in Fig. 3, to securely lock the end to the upper end of the container, thus completing the assembly. Since the chain 17 is attached to the ornament base by passing a link or a snap hook thereto, the ornaments are securely locked in place, and cannot be removed except by separating the base from the chain 17 and removing the base from the container.

15 The above described construction utilizes selected ornaments; and an alternative base indicated as 36 in Fig. 8, and having a permanent ornament 37 mounted thereon, may be used instead.

20 If it be desired to use a material other than leather for the container, a construction such as disclosed in Figs. 9-12 may be used, the assembled identification ornament 38 being preferably entirely of metal, although other suitable mate-

25 rials may be used, and consisting of a base 39, preferably formed of stamped sheet metal, having spaced upstanding flanges 40 terminating in edges 41 which extend towards each other and are spaced from the body of the base, a side flange 30 42 being preferably provided to facilitate mounting and positioning of the ornaments on the base. The ornaments 43 are similar in construction to the ornaments 31, and have grooves 44 at the upper and lower ends thereof to facilitate sliding engagement with the edges 41, the first ornament resting against the flange 42.

The ornament base has a head 45 provided with an opening 46, for attachment to a chain or other connection, and has a projecting finger 47 at the lower end thereof, spacing formations 48 and 49 being provided to keep a cover member 50 at suitable spaced relation to the base. The cover member 50 has sides 51 and an inner frame portion 52, the lower end having a slot 53 there- 45 through and the upper end being cut to provide a central resilient finger 54. When the initials or other ornaments are assembled on the base 39, the cover 50 is positioned so as to pass the tongue 47 through the slot 53, the resilient finger 50 54 then snapping over the edge 55 of the opening 46 to lock the parts together, the finger 54 being preferably curved so as to snappingly engage

the edge 55 and to provide a small finger engageable extension projecting slightly at the back to facilitate detachment of the cover from the base; the edges 51 preferably completely enclose the edges of the base so as to provide an attractive assembly. 5

While I have described specific constructional embodiments of my invention, any desired changes in the material used for the parts, in their relative arrangement and assembly, and in their relative proportions, may be made to suit the requirements for different designs, without departing from the spirit and the scope of the invention as defined in the appended claims.

I claim:

1. In an identification ornament, a base having spaced flanges, said flanges having retaining means extending toward each other, an ornament device having complementary retaining means slidably engageable with said flange means, and 20 a cover secured to said base and having a frame opening, the sides of said frame opening engaging the sides of said ornament device to lock said device to said base.

2. In an identification ornament, a base having spaced flanges, said flanges having edges extending toward each other, an ornament device having grooves and slidably engageable with said edges, and a cover secured to said base and having a frame opening, the sides of said frame opening engaging the sides of said ornament device to lock said device to said base. 25

3. In an identification ornament, a rigid, metallic base having spaced flanges, said flanges having edges extending toward each other, an ornament device having grooves and slidably engageable with said edges, and a flexible, non-metallic cover secured to said base and having a frame opening, the sides of said frame opening engaging the sides of said ornament device to 40 lock said device to said base. 35

4. In an identification ornament, a base having spaced flanges, said flanges having edges extending towards each other, an ornament device having grooves and slidably engageable with 45 said edges, and a cover secured to said base and having a frame opening, the sides of said frame opening engaging the sides of said ornament device to lock said device to said base, said base having an extension provided with an opening. 50

WILLIAM FORSTNER.
